UNITED STATES PATENT OFFICE

CHARLES R. SHORT, OF DAYTON, OHIO, ASSIGNOR TO MORaine PRODUCTS COMPANY, OF DAYTON, OHIO, A CORPORATION OF OHIO

METHOD OF BRIQUETTING BUSHINGS

Application filed February 24, 1930. Serial No. 430,836.

This invention relates to means and method of briquetting bushings or similar articles from powdered granular or semi-plastic materials.

In the Patent 1,642,348 issued Sept. 13, 1927, to H. M. Williams et al. there are disclosed various formulæ and method of making self lubricating bearing bushings from metal powder and other powdered ingredients.

Now the general object of this present invention is to provide a briquetting apparatus and method of briquetting such powdered ingredients into bushings whose walls will have a very uniform thickness and density. When compacting powdered materials into relatively thin wall bushings it is often difficult to insure the proper filling of the narrow die cavity with the loose powder charge since such powder will not flow freely and perfectly as a liquid, and hence small unfilled spaces may occur in the die cavity or the loose charge will not be equally shaked down to a uniform density throughout the die cavity.

Now this invention provides for very uniformly filling the die cavity with the loose charge of powder to produce a finished article of uniform density and thickness of wall. This is accomplished by providing the die cavity with a longitudinally movable and rotatable central core. The central core is in withdrawn position from the die cavity when the filling with the loose powder is begun, then the central core is moved slowly upward toward its core-forming position and simultaneously rotated during the filling with the loose charge, whereby the loose powdered particles are equally distributed peripherally in the annular space about the core. A very uniform and complete filling of the annular die cavity with the loose powder or granular material is thus obtained.

Further objects and advantages of the present invention will be apparent from the following description, reference being had to the accompanying drawings wherein a preferred embodiment of one form of the present invention is clearly shown.

In the drawings:

Fig. 1 is in part a side elevation and in part

a vertical section through a briquetting press made according to this invention.

Figs. 2, 3 and 4 are views illustrating various positions of certain operating parts. Fig. 2 illustrates the withdrawn position of the central core at the time the loose charge begins to fall within the die cavity.

Fig. 3 shows the die cavity about half full with the loose powder and the core moving upwardly with a rotating motion with its upper end approximately even with the level of the powder.

Fig. 4 shows the core at its top-most position, and the punch descending to compact the material.

Similar reference characters refer to similar parts throughout the several views.

Numeral 20 designates the stationary die having the open end die cavity 21 therein. The lower tubular ram 22 is received within the lower open end of cavity 21 and a rotatable and vertically reciprocatable core 23 moves within the tubular ram 22. Fig. 2 shows the core 23 at its lower-most position leaving the cavity 21 entirely unobstructed. The loose powder enters cavity 21 in a stream from the hopper 26 and the vibrating filling shoe 27. The core 23 moves upwardly with a rotating motion as the cavity is filled with the loose charge, preferably at such a rate that the upper end thereof keeps substantially even with the upper lever of the loose powder. Core 23 is rotated during its ascent at such a rate as will best aid in distributing the loose powder peripherally thereabout. Just prior to the time core 23 reaches the position shown in Fig. 4, the filling shoe 27 is swung across the upper surface of die 20, leaving the die cavity filled approximately flush with its top with the loose powder. Core 23 then moves slightly beyond the upper surface of die 20, as shown in Fig. 4, and the parts are then in position for the descent of the annular compacting punch 25.

The core 23 is received within the bore of the punch 25 and thus acts as a pilot for the punch, as will be clear from Fig. 4. After the material is briquetted into a compact bushing, which may have only about half the volume of the loose powder in the annular

die cavity before briquetting, punch 25 is withdrawn upwardly from the cavity and preferably at the same time the core 23 is withdrawn downwardly from within the formed bushing to the position shown in Fig. 2. The tubular ram 22 is then caused, by suitable mechanism, to move up and eject the formed bushing from cavity 21. This ejecting operation is greatly facilitated by the previous withdrawal of core 23 from the bushing since the high pressure contact between the formed bushing and its outer die walls is very materially decreased when the inner core is withdrawn. By thus reducing the friction between bushing and die, the wear upon the die is greatly reduced, and hence the cost of replacing worn dies is very materially decreased.

One form of machine for supporting and actuating the parts heretofore mentioned will now be described:

This machine (see Fig. 1) includes a base 10 which supports the main frame 11, providing bearings for a power-driven main shaft 15 which carries a crank pin 65. Crank pin 65 is connected with the cross head pin 66 by connecting rod 67. Pin 66 has bearing upon cross head 69 which is vertically reciprocable between guides 70 supported upon the main frame 11. The bottom end of cross head 69 has fixed thereto a socket member 72 which receives the enlarged head 73 of annular punch 25. The reciprocating movement of punch 25 will now be clear. The other moving parts hereinabove described are all driven from the drive shaft 15 by suitable cams and hence may be suitably timed with the movement of punch 25 and with each other.

The filling shoe 27 is pivoted at the pivot pin 28 and is actuated to swing and to oscillate about the pivot 28 by cam 30 on main shaft 15. The lever 31 has a fixed pivot at 32, a cam follower 33 riding in cam groove 30, and a link 34 connecting its lower end to the filling shoe 27 whereby said shoe will be brought into registration with the die cavity 21 at the proper time for filling same and then give several rapid oscillations or shakes in order to discharge the loose molding powder in a more or less steady stream into the die cavity 21.

An appreciable time is required to thus fill the die cavity, during which time core 23 is raised from the position shown in Fig. 2 to that shown in Fig. 4 by means of a lever 35 having a fixed pivot at 36 and a forked end 37 engaging spaced flanges 38 fixed to core 23. Lever 35 is actuated by driven cam 40 on main shaft 15, a cam follower 41 on bell crank lever 42, pivoted at 43, and a long link 44. Simultaneously with its up movement, core 23 is rotated by a pinion 45 which slides longitudinally upon the square portion 46 on the lower end of core 23. Pinion 45 is

geared to the sliding rack 47 which is actuated by the long lever 48, pivoted at 49, and having a cam follower 51 riding within the cam groove 50. By means of this or any other suitable mechanism the core 23 may be rapidly rotated while it moves up through the loose powder charge as it fills the die cavity 21. Core 23 remains stationary in the position shown in Fig. 4 until after the material is compacted by punch 25, after which it is withdrawn from the formed bushing to position shown in Fig. 2. Preferably cams 40 and 50 are so related that core 23 is withdrawn from the formed bushing without rotation until it clears the bushing, after which it may be rotated idly to bring rack 47 back to its initial position as shown in Fig. 2. Main punch 25 preferably begins its descent while core 23 is yet moving up and preferably engages core 23 shortly after it reaches its top position as shown in Fig. 4. The powdered material is compacted under a very high pressure by punch 25 into a quite hard rigid bushing, after which punch 25 is immediately withdrawn from the cavity 21 and core 23 is withdrawn downwardly from its position within the formed bushing by the cam 50.

The formed bushing is now ejected by the up movement of the annular ejecting ram 22 which is actuated by lever 55 pivoted at 56 and having a forked end 57 engaging the two flanges 58 fixed to the large sleeve 59 which rigidly supports the ejecting ram 22 as clearly shown in Fig. 1. Lever 55 is actuated by cam 60 on main shaft 15 through the cam follower 61 on bell crank lever 62, pivoted at 63, and the connecting link 64. After ejection of the formed bushing, the parts all return to the position shown in Fig. 2, whereupon the cycle may be repeated. When the filling shoe 27 swings across the top face of the die 20, it engages the previously ejected bushing and pushes it laterally out of the way and into a suitably located chute.

While the form of embodiment of the present invention as herein disclosed, constitutes a preferred form, it is to be understood that other forms might be adopted, all coming within the scope of the claims which follow.

What is claimed is as follows:

1. The steps in the method of briquetting cored bodies comprising: withdrawing the mold core from the briquetting mold cavity, then filling said cavity with the loose material to be briquetted and simultaneously moving said core through the loose material with a rotating motion to distribute the charge uniformly within the cavity, then compacting the charge by a hollow punch.

2. The steps in the method of briquetting cored bodies comprising: filling the mold cavity with the loose powdered material to be briquetted, and while so filling moving the mold core through the material with a rotat- ing motion whereby to more evenly distribute

the charge as it enters, then compacting the charge with a hollow punch fitting upon the core.

3. The steps in the method of briquetting annular bushings comprising: pouring the loose material into the mold cavity while the mold core is moving to its core-forming position in the mold cavity, and simultaneously rotating said core to uniformly distribute the charge as it enters the cavity.

4. The steps in the method of briquetting annular bushings comprising: moving the mold core axially to its core forming position in the mold cavity with a rotating motion and simultaneously pouring the loose material into the cavity to fill same at such rate as to maintain the level of the material approximately even with the advancing end of the core.

20 In testimony whereof I hereto affix my signature.

CHARLES R. SHORT.
